UNITED STATES PATENT OFFICE.

LEWIS M. CROCKETT, OF KALAMAZOO, MICHIGAN.

MACHINE FOR SETTING UP CARTONS.

1,311,321.

Specification of Letters Patent.

Patented July 29, 1919.

Application filed October 18, 1918. Serial No. 258,766.

To all whom it may concern:

Be it known that I, LEWIS M. CROCKETT, a citizen of the United States, residing at Kalamazoo, county of Kalamazoo, State of Michigan, have invented certain new and useful Improvements in Machines for Setting Up Cartons, of which the following is a specification.

This invention relates to a machine for 10 setting up cartons.

The main objects of this invention are:

First, to provide a machine for setting up and closing the flaps of one end of a carton, which is entirely automatic.

Second, to provide a machine for setting up and closing the flaps of one end of a carton, which is of large capacity.

Third, to provide, in a machine for setting up cartons, an improved feed means.

Fourth, to provide, in a machine for setting up and closing the end flaps of cartons, an improved means for setting up and supporting the cartons while the end flaps are folded.

Fifth, to provide a machine of the class described with an improved flap closing means.

Sixth, to provide, in a machine of the class described, an improved means for ejecting 30 the cartons.

Further objects, and objects relating to structural details, will definitely appear from the detailed description to follow.

I accomplish the objects of my invention 35 by the devices and means described in the following specification. The invention is clearly defined and pointed out in the claims.

A structure which is a preferred embodiment of my invention is clearly illustrated 40 in the accompanying drawing, forming a part of this specification, in which:

Figure I is a front perspective view of a structure embodying the features of my invention, the crank only of the power means 45 being shown.

Fig. II is an end view looking from the left of Fig. I.

Fig. III is a detail central transverse section on a line corresponding to line 3—3 of Fig. IV.

Fig. IV is a detail longitudinal section through the hopper and feed means on a line corresponding to line 4—4 of Fig. III.

Fig. V is an inverted view of the base or

bed plate, showing the various mechanisms 55 mounted thereon.

Fig. VI is a detail inverted view of the hopper and feed mechanism.

Fig. VII is a detail inverted view of the operating mechanism of one of the inner 60 flap folders with the parts shown in initial position.

Fig. VIII is a view of the parts shown in Fig. VII in a partially actuated position.

Fig. IX is a detail section on a line corresponding to line 9—9 of Fig. VIII.

Fig. X is an inverted detail view showing the details of the operating mechanism for the other inner flap folder.

Fig. XI is a detail plan view of the inner 70 flap folders, their initial position being shown by full lines and their actuated position by dotted lines.

Fig. XII is an enlarged detail section on a line corresponding to line 12—12 of Fig. 75 V, showing details of the outer flap folder and closing means and the actuating means therefor.

Fig. XII^A is an enlarged detail section on a line corresponding to line 12^A—12^A of 80 Fig. XII, showing the lost motion operating connections for the main actuating member to the outer flap folder slide or carriage.

Fig. XIII is a detail longitudinal section 85 corresponding to that of Fig. XII, showing the outer flap folding and closing means in partially actuated position.

Fig. XIV is a view similar to Fig. XIII, showing the folding and closing means in 90 fully actuated position.

Fig. XV is a detail transverse section on a line corresponding to line 15—15 of Figs. 95 V and XI, showing details of the carton erecting means.

Fig. XVI is a detail section on a line corresponding to line 16—16 of Fig. XII, showing details of the operating means for the carton setting up mechanism, the parts being indicated on their forward stroke, the position of the parts at the end of the forward stroke being indicated by dotted lines.

Fig. XVII is a similar view to that of Fig. XVI with parts indicated in their return position by dotted lines.

Fig. XVIII is an enlarged detail section 105 on a line corresponding to line 18—18 of Fig. V, showing the relation of the main

actuating slide and details of the operating connections.

Fig. XIX is a detail longitudinal section showing details of the carton ejector.

5 Fig. XX is a detail longitudinal section corresponding to that of Fig. XIX, showing the parts in another position.

10 Fig. XXI is a detail longitudinal section corresponding to that of Fig. XX, showing the parts in still another position.

Fig. XXII is a detail side elevation of parts shown in Fig. XXI in still another position.

15 Fig. XXIII is a detail elevation of parts of the feed mechanism actuating means.

Fig. XXIV is an enlarged detail section through the main actuating pitman on a line corresponding to line 24—24 of Fig. I.

20 In the drawing similar reference characters refer to similar parts throughout the several views and the sectional views are taken looking in the direction of the little arrows at the ends of the section lines.

Referring to the drawing, the base or bed 25 plate 1 is, in practice, mounted on a table or suitable support, not illustrated. 2 represents the crank of the power or drive shaft.

The hopper 3 is supported on brackets 4 so as to overhang parts of the mechanism.

30 The cartons 5 illustrated are arranged in the hopper in the knockdown or "flat" condition, the cartons illustrated being such as are quite generally used for bottles and are scored so that they may be retained in set

35 up form by the flaps at one end. I have shown the cartons mainly in conventional form and those illustrated are provided with opposed inner flaps 6 and an outer flap 7 having a tongue 8 adapted to be tucked into

40 the carton at the edges of the inner flaps in the well-known manner, my machine being designed to set up and close one end of a carton ready to receive the bottle or package which it is to contain.

45 The cartons are discharged from the hopper one by one into the setting up mechanism consisting of a fixed abutment 9 and the swinging angular set up member 10 which is pivoted on the base at 11. These

50 members are disposed oppositely so that the cartons are discharged from the hopper with one longitudinal edge lying in the angle formed by the abutment member 9 and the base and the other upon the member 10 near

55 the angle thereof,—see Fig. III. When this member 10 is actuated it engages the edge of the collapsed carton and swings the same upwardly and presses inwardly thereon and, owing to the cartons being previously scored along folded lines, it is expanded or set up as indicated by dotted lines in Fig. III.

60 The set up member 10 is provided with an arm 12 projecting downwardly through a slot 13 in the base plate 1,—see Fig. XV.

This arm is connected by the link 14 to a 65 lever 15 pivoted at 16 on the under side of the base plate. This lever is actuated by the cam 17 on the actuating member 28 which is reciprocatingly mounted on the under side of the bed plate. The lever 15 is provided with 70 a roller 19 adapted to travel on this cam 17.

To provide a gradual closing movement for the set up member 10 and a quick opening movement therefor the cam 17 is provided with a drop or recess 20 closed by the 75 bridge piece 21 on the work or forward stroke of the cam,—see Fig. XVI. This bridge piece on the forward stroke of the cam swings to the position indicated by dotted lines in Fig. XVI, so that the movement 80 of the lever is substantially uniform. When the roller passes over this bridge piece on the forward or work stroke the bridge piece, which is carried by the spring 22, swings down so that on its return the roller drops 85 into the recess providing a quick return movement for the setting up member 10, the return being effected by the spring 23 connected to the base plate at 24 and to the lever in front of its pivot 16,—see Fig. V. 90

On the under side of the bed 1 is a way 95 comprising a pair of members 25 for the outer flap folder slide or carriage 26. This carriage 26 carries a way 27 for the inner actuating slide or member 28. The operating pitman 29 is connected to this actuating member 28 at 30. The actuating member 28 has a lost motion connection to the flap folder carriage 26, the carriage 26 being provided with a pin 31 and the actuating member 28 with coacting stop or abutment members 32 and 33,—see Figs. XII and XIII^A.

The folder carriage 26 carries a bracket 34 in which the shank 35 of the outer flap 105 folder 36 is slidably mounted, the bracket having a pair of upwardly projecting arms 37 and 38 with aligned holes therein for the shank of the folder. The shank of the folder is provided with a stop 39 which engages the end 40 of the slot 41 when the folder 36 reaches the end of its forward stroke. The folder 36 is rearwardly curved so that it engages the end of the outer flap and as the folder moves forward swings it 115 downwardly and turns its tongue inwardly, the folder being provided with a tongue guide or tucker 42 which enters the carton guiding the tongue 8 into the carton between the edges of the inner flaps 6 and the adjacent wall of the box. 120

To completely close the outer flap I pivotally mount a flap closer 43 on the folder 36 at 44 so that it may be swung down at each side of the folder, the flap closer being bifurcated as shown in Fig. I. This flap closer 43 is actuated by the pushers 45 mounted on the sides of the arms 37 and 38 of the folder 125

supporting bracket 34 to engage projections 46 on the flap closer. The flap folder 36 being slidably supported on its carriage is stopped when its stop 39 engages the stop 40 on the bed plate so that on the continued forward movement of the slide 26 the pushers 45 actuate the flap closer 43. On the return movement of the carriage the parts are returned to their initial position by the 10 spring 47 on the shank of the flap folder 36, which spring is adjusted by the nut 48 threaded on the shank and the spring 49 on the pivot 44 of the flap closer 43.

Prior, however, to the folding of the 15 outer flap 7 the inner flaps 6 are successively folded by means of the inner flap folders 50 and 51. These are, in practice, spring members mounted on posts 52 and 53, respectively, projecting through slots 54 and 55 20 in the base plate 1. These posts are carried by links 56 and 57 and engage slots 58 and 59 in the bell crank levers 60 and 61, respectively. These levers are pivoted at 62 and 63, respectively, to arms 64 and 65 on the 25 slides 66 and 67. The links 56 and 57 have slots 68 therein engaging pins 69 on the levers so that when the slides are actuated the posts 52 and 53 are swung in their slots and give a limited pivotal movement, the 30 movement being timed so that first one of the inner flaps is folded and then the other is folded thereon. The slides 66 and 67 are disposed oppositely on opposite sides of the actuating member 28.

35 The slide 66 is supported by the bracket 70 at its rear side and also the slotted stop or dog 71 slidably supported in the bracket 72 and urged yieldingly inward by the spring 73. This stop or dog 71 is adapted 40 to coact with the notch or keeper 74 on the slide. The slide 66 is also supported on its inner edge by a block 75. On the actuating member 28 is a spring-pressed pawl 76 adapted to engage a tooth 77 on the slide 66 45 and carry the slide forward until the pawl is released by engaging with the tip 78 of the bracket 70 which constitutes a trip. Prior to the releasing of the pawl 76 the catch 71 engages the stop 74 retaining the 50 slide until the dog 71 is released by the pawl 76 which constitutes a trip therefor. When released the slide is quickly returned by means of the coiled spring 79 connected to the base plate at 80 and to the arm 64 at 55 81. The slide 67, best shown in Figs. V and X, is similarly supported and actuated, the parts being of slightly different proportions and somewhat differently positioned as the inner flap folders are designed to operate 60 successively.

The actuation of the setting up member lever and these inner flap folders and the outer flap folder is timed so that the setting up member is actuated first. The inner

flap folders are then successively actuated 65 and then, through the lost motion connection described, the outer flap folder and closer is actuated and returned during the forward stroke of the actuating member, while the setting up member and the ejecting means are actuated during the return stroke of the actuating member.

The ejecting member 82 is pivotally mounted at 83 on the slide or carriage 84 mounted on the under side of the bed 1. 75 The springs 85 are secured at one end to the bed and at the other end to the slide to actuate it on its work stroke. The ejector projects through a slot 86 in the bed to engage the carton, it being held yieldingly upward by the spring 87. On the work stroke of the actuating member the ejector is brought into engagement with the cam 88 and carried downwardly out of the way of the succeeding carton. When in its initial 85 position the ejector projects through the bed at the rear of the carton as shown in Fig. XIX.

The ejector is actuated and controlled by the extension bar 89 of the actuating member 28, the forward end of the bar being supported by the bracket 90. This bracket carries the stop 91 with which the dog 92 on the ejector slide engages when the ejector is in its retracted position. This dog is released by the cam 93 on the bar 89. The dog 92 is spring-pressed as is also the pawl 94 adapted to engage notches 95 in the bar for returning the ejector, the operation being as follows:

The parts are normally in the position shown in Fig. XX, the actuating member then being in its fully retracted position and the ejector in its actuated position. On the return movement of the actuating member the pawl 94 engages with the notches 95 of the bar 89 carrying the ejector to its set position,—see Fig. XIX. The pawl 94 is released from the notch 95 by its engagement with the stop 91. The dog or catch 110 92 rides over this stop and engages on the rear side thereof, thus holding the ejector in its return position under tension of the spring 85 until the dog 92 is released by the cam 93 on the bar permitting the actuation 115 of the ejector carriage by its actuating spring described.

The feed mechanism is also actuated from the actuating member 28 which is provided with a cam 97 coacting with an arm 98 of 120 the rock shaft 99 mounted on the under side of the bed in bearings 100,—see Fig. V.

The rock shaft 99 has an arm 101 engaging a slot 102 in the bell crank lever 103 pivoted on a suitable hanger at 104 with one 125 arm projecting through a slot in the bed 1. This arm is connected by a link 105 to a bar-like cam member 106 slidably mounted

in a suitable way 106' at the rear side of the carton hopper. This hopper is adapted to support the cartons in the flat condition stacked one upon the other as shown in Fig. 5 III. The cartons are fed or discharged from the hopper one by one, the discharge mechanism consisting of coacting levers 107 and 108 mounted in pairs on pivots 109 and provided with carton engaging fingers 110 10 and 111, respectively, there being four of these pairs of levers disposed oppositely. The outer ends of these levers project at the ends of the hopper and are connected for simultaneous actuation by the crossed links 15 112, preferably having springs 113 therein. With this connection the four levers 107 are simultaneously actuated to and from carton engaging position, while the four levers 108 are similarly actuated. To actuate 20 the levers to carton engaging position the cam member 106 is provided with cams 114, while the levers 108 are provided with projections 115 coacting with these cams. The levers 107 have projections 116 coacting 25 with cams 117 of the cam member 106. The cam member 106 is provided with an adjustable stop 118 limiting its return movement, it being returned by the spring 119 connected to the bell crank lever 103 and to a bracket 120 on the bed 1. The discharge 30 finger levers are retracted by the coiled springs 121 connected to the hopper wall and to the rear finger levers.

In the initial position of the parts as shown 35 in Figs. III and IV the fingers 110 support the stack of cartons. When the finger levers are actuated from this position these fingers 110 are retracted and the fingers 111 projected, the fingers 111 being pointed so that 40 they pass above the bottom carton of the stack supporting the stack, the fingers 110 being then retracted to discharge the bottom carton on to the fixed supports 122 at the rear and the swinging support 123 at the 45 front of the hopper. The support 123 extends below the plane of the support 112 so that when a carton is discharged therefrom its front edge drops behind the abutment 9 before its rear edge drops on to the setting 50 up member 10, as shown in Fig. III.

The support 123 is pivoted at 124 and held 55 yieldingly in position by the coiled spring 125 around its pivot. The support 123 is actuated to release the carton by the discharge levers 107 at the rear, the support having arms 126 engaging beveled ends or cams 127 on the levers so that when the levers are actuated to their supporting position the support 123 is actuated to discharge 60 the carton and when the levers are retracted to discharge the carton the support swings to its supporting position.

The cartons are guided by the fixed guides 128 and 129. On the bed are fixed position- 65 ing guides 130, 131 and 132. To insure the

release of the cartons from the fingers 111 I provide clearing springs 133 secured to the hopper at their upper ends to project downwardly in proximity to the fingers 111. These springs have portions 134 which engage on the levers at their ends 108 so that when the levers are actuated the springs are pressed against the lower cartons of the stack. When the levers are retracted the pressure is released allowing the carton to 75 drop on to the fingers 110 and clearing the fingers 111. The upper end of the hopper is supported by the uprights 135 mounted on the base bar 136.

With this arrangement of parts the cartons are automatically delivered, set up, and closed at one end.

To relieve the parts from undue strain in the event of clogging I form the pitman 29 of sections 138 and 139, the section 139 having a sleeve 140 thereon slotted at 141 to engage pins 142 on the section 138. A spring 143 is disposed between the sections and is of such tension as to normally operate them but yields in the event of any mechanism 90 becoming clogged or wedged.

I have illustrated and described my improvements in the form in which I have embodied the same for the setting up of cartons of comparatively small size.

I have not attempted to illustrate or describe the various modifications and adaptations which I contemplate as I believe the disclosure made will enable those skilled in the art to which my invention relates to embody or adapt the same as may be desired.

Having thus described my invention, what I claim as new and desire to secure by Letters Patent, is:

1. In a structure of the class described, 105 the combination of a carton setting up means, a pair of inner flap folders, an outer flap folder and closing means, an actuating member, operating connections therefor to said setting up member and said inner flap 110 folders and said outer flap folder and closing means whereby the setting up means is first actuated, the inner flap folders are successively actuated and then the outer flap folder and closer actuated, means for feeding cartons to said setting up means actuated by said actuating member, an ejector, and operating means therefor including said actuating member whereby the erected cartons are ejected on the return stroke of the 115 actuating member.

2. In a structure of the class described, 120 the combination of a carton setting up means, a pair of inner flap folders, an outer flap folder and closing means, a reciprocating actuating member, operating connections therefor to said setting up member and said inner flap folders and said outer flap folder and closing means whereby the setting up means is first actuated, the inner 125

flap folders are successively actuated and then the outer flap folder and closer actuated, and means for feeding cartons to said setting up means actuated by said actuating member.

3. In a structure of the class described, the combination of a pair of inner flap folders, an outer flap folder and closing means, a reciprocating actuating member, operating 10 connections therefor to said inner flap folders and said outer flap folder and closing means whereby the inner flap folders are successively actuated and then the outer flap folder and closer actuated, an ejector, and 15 operating means therefor including said actuating member whereby the erected cartons are ejected on the return stroke of the actuating member.

4. In a structure of the class described, 20 the combination of a pair of inner flap folders, an outer flap folder and closing means, a reciprocating actuating member, operating connections therefor to said inner flap folders and said outer flap folder and closing 25 means whereby the inner flap folders are successively actuated and then the outer flap folder and closer actuated.

5. In a structure of the class described, 30 the combination of a carton setting up means, flap folders, a reciprocating actuating member, operating connections therefor to said setting up member and flap folders, means whereby the setting up means is first actuated and then the flap folders are actuated, means for feeding cartons to said setting 35 up means actuated by said actuating member, an ejector, and operating means therefor including said actuating member whereby the erected cartons are ejected on the return stroke of the actuating member.

6. In a structure of the class described, 40 the combination of carton setting up means comprising a side abutment member, an angular pivotally mounted setting up member disposed to swing to and from said abutment member, means for feeding cartons with one of their longitudinal edges against said abutment member and the opposite edge resting 45 on said setting up member so that when the 50 setting up member is swung on its pivot such edge is engaged by the angle of the setting up member and the carton expanded as the setting up member swings forwardly, an arm on said setting up member, a pivoted actuating lever provided with a roller, a link connecting said lever to said arm, an actuating cam for said lever having a drop or recess therein, a yieldingly mounted bridge member for said recess adapted to be engaged by the roller on said lever on the forward movement of the cam to close the recess, said bridge being spring mounted so that it swings inwardly when the roller has passed allowing the roller to drop into the 55 recess and provide a quick return for the set-

ting up member on the return movement of the cam.

7. In a structure of the class described, 60 the combination of carton setting up means comprising a side abutment member, a pivotally mounted setting up member disposed to swing to and from said abutment member, an arm on said setting up member, a pivoted actuating lever provided with a roller, a link connecting said lever to said arm, an actuating cam for said lever, having a drop or recess therein, a yieldingly mounted bridge member for said recess adapted to be engaged by the roller on said lever on the forward movement of the actuating member 65 to close the recess, said bridge being spring mounted so that it swings inwardly when the roller has passed allowing the roller to drop into the recess and provide a quick return for the setting up member on the return 70 movement of the cam.

8. In a structure of the class described, 75 the combination of a base, a side abutment member mounted thereon, an angular setting up member pivotally mounted on said base in 80 opposed relation to said abutment member to swing to and from the same, means for feeding cartons in the flat with one longitudinal edge resting on the base against said abutment member and the opposite edge 85 resting on said setting up member so that when the setting up member is swung on its pivot it is engaged by the angle thereof and the cartons are expanded to erected position resting on said base with said abutment supporting one side and said setting up member the opposite side and top, means for closing 90 the rear flaps adapted to act upon the carton while the same is retained by said setting up means, an actuating member, 95 supporting one side and said setting up member the opposite side and top, means for closing the rear flaps adapted to act upon the carton while the same is retained by said setting up means, an actuating member, 100 operating connections therefor to said setting up means and flap folding means whereby they are actuated on the forward stroke of 105 said actuating member, a carton ejector, and operating connections therefor to said actuating member whereby the ejector is actuated on the return stroke of the actuating member.

9. In a structure of the class described, 110 the combination of a base, a side abutment member mounted thereon, an angular setting up member pivotally mounted on said base in 115 opposed relation to said abutment member to swing to and from the same, means for feeding cartons in the flat with one longitudinal edge resting on the base against 120 said abutment member and the opposite edge resting on said setting up member so that when the setting up member is swung on its pivot it is engaged by the angle thereof and the cartons are expanded to erected position 125 resting on said base with said abutment supporting one side and said setting up member the opposite side and top, and means for closing the rear flaps adapted to act upon 130

the carton while the same is retained by said setting up means.

10. In a structure of the class described, the combination of a side abutment member, 5 a setting up member pivotally mounted in opposed relation to said abutment member to swing to and from the same, so that when a carton in the flat is disposed with one longitudinal edge resting against said abut- 10 ment member and the opposite edge resting on said setting up member it is engaged there- by and the carton expanded to erected posi- tion when said setting up member is actu- ated, means for closing the rear flaps adapted 15 to act upon the carton while the same is re- tained by said setting up means, an actuating member, operative connections therefor to said setting up means and flap folding means whereby they are actuated on the forward 20 stroke of said actuating member, a carton ejector, and operating connections therefor to said actuating member whereby the ejector is actuated on the return stroke of the actu- ating member.
25. 11. In a structure of the class described, the combination of a rearwardly curved flap folder member having a flap tongue guide finger at one edge adapted to enter a carton and guide a flap tongue into it, said flap 30 folder member being provided with a shank, a reciprocating carriage on which said shank is slidably mounted, a spring on said shank for urging said flap folder yieldingly forward, a nut on said shank for ad- 35 justing the tension of said spring, a stop for limiting the forward movement of said folder member, a flap closer pivotally mounted on said folder member, a spring for hold- 40 ing said flap closer normally in retracted position, and an actuating member on said carriage engaging said flap closer and actu- ating the same on the continued movement of 45 said carriage after the engagement of said folder member stop.
50. 12. In a structure of the class described, the combination of a rearwardly curved flap folder member having a flap tongue guide finger at one edge adapted to enter a carton and guide a flap tongue into it, said flap 55 folder member being provided with a shank, a reciprocating carriage on which said shank is slidably mounted, a spring for urg- 60 ing said flap folder yieldingly forward, a stop for limiting the forward movement of said folder member, a flap closer pivotally mounted on said folder member, a spring for holding said flap closer normally in retracted position, and an actuating member on said carriage engaging said flap closer and actu- 65 ating the same on the continued movement of said carriage after the engagement of said folder member stop.

13. In a structure of the class described, the combination of a rearwardly curved 65 flap folder member having a flap tongue

guide finger at one edge adapted to enter a carton and guide the flap tongue into it, a reciprocating carriage on which said folder member is slidably mounted, a spring for holding said folder member yieldingly forward, a stop limiting the forward move- 70 ment of said folder member engaging prior to the carriage reaching the limit of its forward movement, a flap closer pivotally mounted on said folder member, a spring for holding said flap closer normally in its re- tracted position, and an actuating member on said carriage engaging said flap closer and actu- ating the same on the continued move- 75 ment of the carriage after the com- 80 pletion of the work stroke of the folder member.

14. In a structure of the class described, the combination of a flap folder member, a reciprocating carriage on which said folder 85 member is slidably mounted, a spring for holding said folder member yieldingly for- 90 ward, a stop limiting the forward move- ment of said folder member engaging prior to the carriage reaching the limit of its forward movement, a flap closer pivotally mounted on said folder member, a spring for holding said flap closer normally in its re- tracted position, and an actuating member on said carriage engaging said flap closer 95 and actu- ating the same on the continued move- ment of the carriage after the comple- 100 tion of the work stroke of the folder member.

15. In a structure of the class described, 100 the combination of a rearwardly curved flap folder member having a flap tongue guide finger at one edge adapted to enter a car- 105 ton and guide the flap tongue into it, a flap closer, a reciprocating carriage on which said folder member is slidably mounted, the forward movement of said folder member being stopped prior to the carriage reaching the limit of its forward movement, and means for actu- 110 ating said flap closer on the continued movement of the carriage after the comple- 115 tion of the work stroke of the folder member.

16. In a structure of the class described, the combination of a flap folder member, a 115 flap closer, a reciprocating carriage on which said folder member is slidably mounted, the forward movement of said folder member being stopped prior to the carriage reaching the limit of its forward movement, 120 and means for actu- ating said flap closer on the continued movement of the carriage after the comple- 125 tion of the work stroke of the folder member.

17. In a structure of the class described, 125 the combination of inner flap folders, an outer flap folder provided with a shank, a carriage in which said shank is slidably mounted, an actuating member having a lost motion connection therewith, said folder 130

being inwardly curved to engage and turn a flap downwardly and having a guide finger at its lower edge adapted to enter a carton and guide the flap tongue thereto, 5 actuating means for said inner flap folders including said actuating member, a stop for said flap closer limiting its forward movement, a spring holding said flap closer yieldingly in its forward position on said 10 carriage, a flap closer pivotally mounted on said flap folder, a spring holding said flap closer yieldingly in its inoperative position, and an actuating member for said flap closer mounted on said carriage to engage the flap 15 closer toward the limit of the carriage to actuate the closer and completely close the flap.

18. In a structure of the class described, the combination of inner flap folders, an 20 outer flap folder provided with a shank, a carriage in which said shank is slidably mounted, an actuating member having a lost motion connection therewith, actuating means for said inner flap folders including 25 said actuating member, a stop for said flap closer limiting its forward movement, a spring holding said flap closer yieldingly in its forward position on said carriage, a flap closer pivotally mounted on said flap 30 folder, a spring holding said flap closer yieldingly in its inoperative position, and an actuating member for said flap closer mounted on said carriage to engage the flap closer toward the limit of movement of the 35 carriage to actuate the closer and completely close the flap.

19. In a structure of the class described, the combination of inner flap folders, an 40 outer flap folder provided with a shank, a carriage in which said shank is slidably mounted, an actuating member slidably mounted on said carriage and having a lost motion connection therewith, actuating means for said inner flap folders including 45 said actuating member, a stop for said flap closer limiting its forward movement, a spring holding said flap closer yieldingly in its forward position on said carriage, a flap closer pivotally mounted on said flap folder, 50 a spring holding said flap closer yieldingly in its inoperative position, an actuating member for said flap closer mounted on said carriage to engage the flap closer toward the limit of movement of the carriage to actuate the closer and completely close the flap.

20. In a structure of the class described, the combination of inner flap folders, an 55 outer flap folder, a carriage therefor, an actuating member having a lost motion connection with said carriage, said folder being inwardly curved to engage and turn a flap downwardly and having a guide finger at its lower edge adapted to enter a carton and 60 guide the flap tongue thereto, actuating

means for said inner flap folders including said actuating member, means limiting the forward movement of said outer flap folder, a flap closer, an actuating member for said flap closer mounted on said carriage to engage the flap closer toward the limit of movement of the carriage to actuate the closer and completely close the flap. 70

21. In a structure of the class described, the combination of inner flap folders, an 75 outer flap folder, a carriage therefor, an actuating member having a lost motion connection with said carriage, actuating means for said inner flap folders including said actuating member, means limiting the forward movement of said outer flap folders, a flap closer, and an actuating member for said flap closer mounted on said carriage to engage the flap closer toward the limit of movement of the carriage to actuate the 80 closer and completely close the flap.

22. In a structure of the class described, the combination of a bed member, carton erecting and flap folding and closing means, a reciprocating actuating member therefor, 90 an ejector, a carriage on which said ejector is pivotally mounted, a spring for urging said ejector normally upward, said bed being slotted to receive the ejector, a cam on said bed with which said ejector engages 95 when in its forward position whereby the ejector is withdrawn from engaging position, an actuating spring for said carriage, an ejector actuating bar on said actuating member, a dog for holding said ejector carriage in its set position, a coacting stop, a return pawl on said carriage, said bar having a keeper coacting with said pawl whereby the carriage is retracted on the return movement of the actuating member, said 100 holding dog stop being adapted to disengage said return pawl, and a cam on said bar for releasing said holding dog.

23. In a structure of the class described, the combination of an ejector, a carriage on 110 which said ejector is pivotally mounted, a spring for urging said ejector normally upward, a cam on said bed with which said ejector engages when in its forward position whereby the ejector is withdrawn from engaging position, an actuating spring for said carriage, a reciprocating actuating member, a dog for holding said ejector carriage in its set position, a coacting stop, a pawl on said carriage, said actuating member having 115 a keeper coacting with said pawl whereby the carriage is retracted, said holding dog stop being adapted to disengage said pawl, and a cam on said actuating member for releasing said holding dog. 120

24. In a structure of the class described, the combination of a bed member having 125 folder post guide slots therein, folder supporting posts disposed in said slots, flap folder members mounted on said posts, lon-

gitudinally slotted links on which said posts are mounted, bell crank levers having longitudinal slots in one arm thereof engaged with said posts and pins in the other arm thereof engaged in said longitudinal slots of said link, a reciprocating actuating member, actuating slides to which said bell crank levers are pivotally connected disposed on opposite sides of said actuating member, 5 spring actuating pawls on said actuating member, said slides being provided with keepers with which said pawls coat to actuate the slides, holding dogs for said slides, trips for releasing said actuating pawls from said slides, said actuating pawls being also adapted to release said holding dogs on the continued actuation of said actuating member, return springs for said slides, an outer flap folder, a carriage 10 therefor having a lost motion connection with said actuating member, said folder being yieldingly mounted on its carriage, a stop for said carriage, a flap closer pivotally mounted on said flap folder, and means on 15 said carriage for actuating said flap closer on the continued movement of the carriage after the folder has reached the limit of its forward stroke.

25. In a structure of the class described, 30 the combination of a bed member having folder post guide slots therein, folder supporting posts disposed in said slots, flap folder members mounted on said posts, longitudinally slotted links on which said posts are mounted, bell crank levers having longitudinal slots in one arm thereof engaged with said posts and pins in the other arm thereof engaged in said longitudinal slots of said link, a reciprocating actuating member, actuating slides to which said bell crank levers are pivotally connected disposed on 35 opposite sides of said actuating member, spring actuating pawls on said actuating member, said slides being provided with keepers with which said pawls coat to 40 actuate the slides, holding dogs for said slides, trips for releasing said actuating pawls from said slides, said actuating pawls being also adapted to release said holding dogs, 45 and return springs for said slides.

50 26. In a structure of the class described, the combination of a bed member having folder post guide slots therein, folder supporting posts disposed in said slots, inner flap folder members mounted on said posts, 55 longitudinally slotted links on which said posts are mounted, bell crank levers having longitudinal slots in one arm thereof engaged with said posts and pins in the other arm thereof engaged in said longitudinal slots of said link, a reciprocating actuating member, actuating slides to which said bell crank levers are pivotally connected disposed on opposite sides of said actuating member, slide actuating pawls on said actu- 60 50

ating member, trips for releasing said actuating pawls from said slides, return spring for said slides, an outer flap folder, and a carriage therefor having a lost motion connection with said actuating member. 70

27. In a structure of the class described, the combination of a bed member having folder post guide slots therein, folder supporting posts disposed in said slots, inner flap folder members mounted on said posts, 75 longitudinally slotted links on which said posts are mounted, bell crank levers having longitudinal slots in one arm thereof engaged with said posts and pins in the other arm thereof engaged in said longitudinal slots of said link, a reciprocating actuating member, actuating slides to which said bell crank levers are pivotally connected disposed on opposite sides of said actuating member, slide actuating pawls on said actuating member, trips for releasing said actuating pawls from said slides, return springs for said slides, and a carriage therefor having a lost motion connection with said actuating member. 80

28. In a structure of the class described, the combination of a bed member having folder post guide slots therein, folder supporting posts disposed in said slots, inner flap folder members mounted on said posts, 85 longitudinally slotted links on which said posts are mounted, bell crank levers having longitudinal slots in one arm thereof engaged with said posts and pins in the other arm thereof engaged in said longitudinal slots of said link, actuating slides to which said bell crank levers are pivotally connected disposed on opposite sides of said actuating member, an outer flap folder, and a carriage therefor having a lost motion connection with said actuating member. 90

29. In a structure of the class described,

the combination of a bed member having a folder post guide slot therein, a folder supporting post disposed in said slot, a flap 10 folder member mounted on said post, a longitudinally slotted link on which said post is mounted, a bell crank lever having a longitudinal slot in one arm thereof engaged with said post and a pin in the other arm thereof engaged in said longitudinal slot of said link, a reciprocating actuating member, an actuating slide to which said bell crank lever is pivotally connected, an actuating pawl on said actuating member, said slide being provided with a keeper with which said pawl coats to actuate the slide, a holding dog for said slide, a trip for releasing said actuating pawl from said slide adapted also to engage and release said holding pawl on a 110 continued actuation of said actuating member, a return spring for said slide, an outer flap folder, and a carriage therefor having a lost motion connection with said actuating member. 115

30. In a structure of the class described, the combination of a bed member having a folder post guide slot therein, a folder supporting post disposed in said slot, a flap 5 folder member mounted on said post, a longitudinally slotted link on which said post is mounted, a bell crank lever having a longitudinal slot in one arm thereof engaged with said post and a pin in the other arm 10 thereof engaged in said longitudinal slot of said link, a reciprocating actuating member, an actuating slide to which said bell crank lever is pivotally connected, an actuating pawl on said actuating member, said slide being provided with a keeper with which 15 said pawl coacts to actuate the slide, a holding dog for said slide, a trip for releasing said actuating pawl from said slide adapted also to engage and release said holding pawl 20 on a continued actuation of said actuating member, and a return spring for said slide.

31. In a structure for the class described, the combination of a bed member having a folder post guide slot therein, a folder supporting post disposed in said slot, a flap 25 folder member mounted on said post, a longitudinally slotted link on which said post is mounted, a bell crank lever having a longitudinal slot in one arm thereof engaged 30 with said post and a pin in the other arm thereof engaged in said longitudinal slot of said link, and an actuating member to which said bell crank lever is pivotally connected.

32. In a structure of the class described, the combination of a hopper open at the bottom, pivotally mounted feed levers arranged 35 in oppositely disposed pairs and provided with feed fingers projecting into the hopper when actuated, the feed fingers of the upper levers being pointed, a sliding actuating cam member, the levers at one side of said hopper being provided with projections adapted to coact with the cams of said cam member whereby corresponding levers of 40 the pairs are alternately actuated, springs for retracting said levers, crossed links connecting opposed levers whereby they are simultaneously actuated by said sliding cam member, a clearing spring mounted within 45 said hopper and provided with arms engaging the upper levers and with portions projecting into the hopper to engage the edges of the cartons therein, carton supports at the rear of the hopper adapted to support the 50 rear edges of the cartons when released by the discharge fingers, a coacting pivoted carton support at the front of the hopper whereby the cartons are supported in a forwardly inclined position, said pivoted 55 support being provided with arms engaged by the forward discharge fingers whereby the carton held by said support is discharged on the inward stroke of said levers, carton setting up means to which the cartons are 60 discharged comprising a fixed side abut- 65

ment, a swinging set up member adapted to receive the rear edges of the cartons, and fixed guide members on said bed.

33. In a structure of the class described, the combination of a hopper open at the bottom, pivotally mounted feed levers arranged 70 in oppositely disposed pairs and provided with feed fingers projecting into the hopper when actuated, the feed fingers of the upper levers being pointed, a sliding actuating cam 75 member, the levers at one side of said hopper being provided with projections adapted to coact with the cams of said cam member whereby corresponding levers of the pairs are alternately actuated, springs for 80 retracting said levers, crossed links connecting opposed levers whereby they are simultaneously actuated by said sliding cam member, a clearing spring mounted within said hopper and provided with arms engaging 85 the upper levers and with portions projecting into the hopper to engage the edges of the cartons therein, carton supports at the rear of the hopper adapted to support the rear edges of the cartons when released by 90 the discharge fingers, and a coacting pivoted carton support at the front of the hopper whereby the cartons are supported in a forwardly inclined position, said pivoted support being provided with arms engaged by 95 the forward discharge fingers whereby the carton held by said support is discharged on the inward stroke of said levers.

34. In a structure of the class described, the combination of a hopper open at the bottom, pivotally mounted feed levers arranged 100 in oppositely disposed pairs and provided with feed fingers projecting into the hopper when actuated, the feed fingers of the upper levers being pointed, a sliding actuating cam 105 member, the levers at one side of said hopper being provided with projections adapted to coact with the cams of said cam member whereby corresponding levers of the pairs are alternately actuated, springs for retracting 110 said levers, crossed links connecting opposed levers whereby they are simultaneously actuated by said sliding cam member, and a clearing spring mounted within said hopper and provided with arms engaging 115 the upper levers and with portions projecting into the hopper to engage the edges of the cartons therein.

35. In a structure of the class described, the combination of a hopper open at the bottom, pivotally mounted feed levers arranged 120 in oppositely disposed pairs and provided with feed fingers projecting into the hopper when actuated, the feed fingers of the upper levers being pointed, a sliding 125 actuating cam member, the levers at one side of said hopper being provided with projections adapted to coact with the cams of said cam member whereby corresponding levers of the pairs are alternately actuated, 130

- springs for retracting said levers, crossed links connecting opposed levers whereby they are simultaneously actuated by said sliding cam member, carton supports at the 5 rear of the hopper adapted to support the rear edges of the cartons when released by the discharge fingers, a coacting pivoted carton support at the front of the hopper whereby the cartons are supported in a forwardly inclined position, said pivoted support being provided with arms engaged by the forward discharge fingers whereby the carton held by said support is discharged on the inward stroke of said levers, carton setting up means to which the cartons are discharged comprising a fixed side abutment, a swinging set up member adapted to receive 10 the rear edges of the cartons, and fixed guide members on said bed.
- 15 36. In a structure of the class described, the combination of a hopper open at the bottom, pivotally mounted feed levers arranged in oppositely disposed pairs and provided with feed fingers projecting into the hopper when actuated, the feed fingers of the upper levers being pointed, a sliding actuating cam member, the levers at one side of said hopper being provided with projections adapted to coact with the cams of said cam member 20 whereby corresponding levers of the pairs are alternately actuated, springs for retracting said levers, and crossed links connecting opposed levers whereby they are simultaneously actuated by said sliding cam member.
- 25 37. In a structure of the class described, the combination of a hopper open at the bottom, pivotally mounted feed levers arranged in oppositely disposed pairs and provided with feed fingers projecting into the hopper when actuated, a sliding actuating cam member coacting with the levers at one side of the hopper, springs for retracting 30 said levers, crossed links provided with springs connecting opposed levers whereby they are simultaneously actuated by said sliding cam members, a clearing spring mounted within said hopper and provided with arms engaging the upper levers and with portions projecting into the hopper to engage the edges of the carton therein, a carton support at the rear of the hopper adapted to support the rear edges of the cartons when released by the discharge fingers, 35 and a coacting pivoted carton support at the front of the hopper whereby the cartons are supported in a forwardly inclined position, said pivoted support being provided with arms engaged by the forward discharge fingers whereby the carton held by said support is discharged on the inward stroke of said levers.
- 40 38. In a structure of the class described, the combination of a hopper open at the bottom, pivotally mounted feed levers arranged in oppositely disposed pairs and provided with feed fingers projecting into the hopper when actuated, a sliding actuating cam member coacting with the levers at one side of the hopper, springs for retracting 45 said levers, crossed links provided with springs connecting opposed levers whereby they are simultaneously actuated by said sliding cam member, and a clearing spring mounted within said hopper and provided with arms engaging the upper levers and with portions projecting into the hopper to engage the edges of the carton therein, a carton support at the rear of the hopper adapted to support the rear edges of the cartons when released by the discharge fingers, a coacting pivoted carton support at the 50 front of the hopper whereby the cartons are supported in a forwardly inclined position, said pivoted support being provided with arms engaged by the forward discharge fingers whereby the carton held by said support is discharged on the inward stroke of said levers, and carton setting up means to which the cartons are discharged.
- 55 39. In a structure of the class described, the combination of a hopper open at the bottom, pivotally mounted feed levers arranged in oppositely disposed pairs and provided with feed fingers projecting into the hopper when actuated, a sliding actuating cam member coacting with the levers at one side of the hopper, springs for retracting 55 said levers, crossed links provided with springs connecting opposed levers whereby they are simultaneously actuated by said sliding cam member, a clearing spring mounted within said hopper and provided with arms engaging the upper levers and with portions projecting into the hopper to engage the edges of the carton therein, a carton support at the rear of the hopper adapted to support the rear edges of the cartons when released by the discharge fingers, and a coacting pivoted carton support at the front of the hopper whereby the cartons are supported in a forwardly inclined position, said pivoted support being provided with arms engaged by the forward discharge fingers whereby the carton held by said support is discharged on the inward stroke of said levers.
- 60 40. In a structure of the class described, the combination of a hopper open at the bottom, pivotally mounted feed levers arranged in oppositely disposed pairs and provided with feed fingers projecting into the hopper when actuated, a sliding actuating cam member coacting with the levers at one side of the hopper, springs for retracting 65 said levers, crossed links provided with springs connecting opposed levers whereby they are simultaneously actuated by said sliding cam member, and a clearing spring mounted within said hopper and provided with arms engaging the upper levers and with portions projecting into the hopper to engage the edges of the carton therein.
- 65 41. In a structure of the class described,

the combination of a hopper open at the bottom, pivotally mounted feed levers arranged in oppositely disposed pairs and provided with feed fingers projecting into the 5 hopper when actuated, a sliding actuating cam member coacting with the levers at one side of the hopper, springs for retracting said levers, and crossed links provided with springs connecting opposed levers whereby

they are simultaneously actuated by said 10 sliding cam member.

In witness whereof, I have hereunto set my hand and seal in the presence of two witnesses.

LEWIS M. CROCKETT. [L. S.]

Witnesses:

VIDA DOOLITTLE,

Mrs. MARY SHAFER.
